lin, Germany, a corporation of Germany

Application April 7, 1939, Serial No. 266,511
In Germany April 28, 1938

21 Claims. (CL 179—7.1)

The present invention relates to a circuit arrangement for calculating fees in automatic remote signalling installations and in particular telephone systems. The determination of the fee by means of meters at the exchange does not always satisfy the requirements that subscribers make of the management, as the meter which informs the subscriber from time to time of the basis for the fee calculation shows only the sum of all the fees and does not make provision for the amount of the fee for individual connections to be indicated.

In order that the subscriber may be able to obtain information about individual fees, so-called fee-printing arrangements have been developed which sum all the possible data for the connection (number of the calling subscriber, call direction and number, renewal of conversation, number of fee units, etc.) on a card and form a record for the subscriber of each connection or of each high valued connection.

Since such printing arrangements are comparatively complicated and costly an economic operation is possible only when the apparatus is situated at the exchange, i. e. in common for a number of subscriber's stations. Thus the expense of printing apparatus and of switch means for controlling the said printing apparatus is greater the higher the number of subscribers requiring tickets for the high valued calls which they originate.

The invention depends on the fact that only a comparatively small number of subscribers, namely those who make a number of high valued calls, require tickets supplied from a printing arrangement, while by far the greater number of subscribers require only the determination of the fee by meters in the normal manner.

The invention relates to an economic arrangement whereby the expense of the printing apparatus and the switch means for the operation thereof is reduced as far as possible, this result being obtained by dividing subscribers having access to the same connecting arrangement into two groups, those whose conversation fees are recorded by meters and those for whom a special account is provided by means of a central printing device. The printing device for recording the requisite accounts is connected or is not connected according to the group to which the calling subscriber's set belongs, connections being by switch means associated with the subscribers belonging to one group.

The arrangement according to the invention also permits essential simplification in switching

operations for controlling the printing apparatus in particular for recording the number of the calling subscriber without considerable reduction in the economic working of the system. It is known to hunt for the calling subscriber by means of a central identifying arrangement and then to transfer impulses corresponding to the calling number through a central arrangement to the printing apparatus. Further it is known to provide the subscriber's station with arrangements for transmitting impulse trains corresponding to the calling number. The first method results in difficulties of circuit technique. The second requires considerable expense and is too costly when all subscriber's stations have to be provided with additional apparatus. When, however, as with the present invention recording by printing apparatus is to be performed only for a section of the subscribers the second method results in a simplification in the switching operations for recording the call number, since provision of special apparatus for comparatively few subscribers does not require considerable expense.

In the drawing the idea of the invention is illustrated with reference to an embodiment of the invention. In Fig. 1 two subscribers' stations $Tn1$ and $Tn2$ are shown of which the fees for the subscriber $Tn1$ are recorded merely by the subscriber's meter $Z1$ at the exchange, while for the subscriber $Tn2$ all the data of interest concerning the particular connection is printed on a voucher. It is understood that it is possible to register fees for the subscriber $Tn2$ on a subscriber's meter if necessary. According to the embodiment the printing apparatus is operated only for high valued connections. Fig. 2 shows the sequence of operation of the contacts of the mechanical impulse sender arranged to transmit the telephone number of the subscriber $Tn2$.

In the first place a local connection set up by the subscriber $Tn1$ will be described.

When the receiver is removed the following call circuit is completed: earth, winding of relay $R1$, contact $3t1$, lower talking conductor, junction line $AL1$, subscriber's station $Tn1$, upper talking conductor, junction line $AL1$, contact $2t1$, resistance $W1$, battery, earth. Relay $R1$ energizes and at contact $7t1$ closes and completes the operating circuit for the magnet $D1$ of the preselector $VW1$ earth, battery, wiper d of the preselector $VW1$ in the normal position, contacts $1t1$, $6t1$, magnet $D1$, relay interrupter $RU1$, earth. Under the control of the relay interrupter the magnet receives stepping impulses by

which the wipers of the preselector are operated until they find a free connecting arrangement, for example the group selector GW. The following test circuit is then completed: earth, vertical off normal contact **33K** (closed so long as the group selector is in its normal position) resistance W_{15} , contact **31a**, resistance W_{13} , wiper *c* of the preselector VW_1 , windings I and II of the relay T_1 , contact **1r1**, wiper *d* of the preselector on the contact segment, battery, earth. In this circuit the relay T_1 of the preselector operates and by opening its contact **6t1** interrupts the stepping circuit for the magnet D_1 , and by closing contact **5t1** short circuits the high resistance winding II of relay T_1 so that the free group selector which has been seized is guarded against further seizing. The subscriber's meter Z_1 connected in parallel to winding I of the relay T_1 can operate either in the test or in the locking circuit. Contacts **2t1** and **3t1** open, opening the call loop and relay R_1 is de-energized. Contacts **1t1** and **4t1** close and connect the subscriber T_{n1} to the talking conductors. The following circuit is then completed: earth, battery, winding of the relay A in the group selector, upper talking conductor, wiper *a* of the preselector VW_1 , contact **1t1**, subscriber's loop, contact **4t1**, wiper *b* of the preselector, choke D_r , earth. Relay A operates in this circuit, which also serves to supply the subscriber with feeding current, and removes the short circuit for winding I of relay C by opening contact **31a**, so that this relay operates in the locking circuit. Contact **32c** closes and holds the relay C energised independently of the off normal contact **33K**.

The subscriber now transmits the initial impulse train. Relay A in the group selector receives the impulses and controls the vertical magnet of the group selector (not shown) so that the wipers of the group selector are raised to a particular contact bank. The group selector then hunts in known manner for a free line. In Fig. 1 a repeater UE for time zone metering, shown only in part, is associated with the group selector. This repeater, however, is usually reached by the group selector when the subscriber sets up a high valued connection and the group selector is set corresponding to a particular digit. For local connections the group selector is followed by a further group selector or a final selector.

When the group selector has found a free connecting arrangement the following test circuit is completed, earth, contacts **41c**, **40a**, winding I of relay P, winding II of relay P, the short circuit for which is broken by contact **43c**, wiper *c* of the group selector and battery potential in a subsequent connecting arrangement. The test relay P of the group selector operates in this circuit and by short circuiting the high resistance winding I of relay P at contact **42p** guards the selected connecting arrangement against seizing by another group selector, and by closing contacts **28p** and **29p** switches through the talking conductors of the group selector. The subscriber now transmits further impulse trains necessary for setting up the required connection. Relay A in the group selector also receives these impulses and transfers them over: earth, contacts **41c**, **39a**, upper talking conductor, contact **28p**, wiper *a* of the group selector to the impulse receiving relay of the following connecting arrangement.

When the receiver at the calling substation is hung up after the conversation the circuit for relay A in the group selector is broken and the

relay is de-energized. Contact **31a** closes and the circuit for winding I of relay C is short circuited so that the contacts of this relay are restored to normal. Contact **43c** closes and the winding II of relay P is short circuited. The release of relay P is prevented, however, by the completion of the following seizing circuit: earth, battery, winding III of relay P, contacts **38c**, **28p**, wiper *a* of the group selector and earth in a subsequent connecting arrangement. At contact **30p** the connecting path is held in the direction extending to the calling subscriber and at contact **42p** in the direction extending to the called subscriber. Metering potential is connected to the lower talking conductor from a subsequent connecting arrangement so that the following circuit is completed for the metering relay Z_r in the group selector: battery potential in the subsequent device, lower talking conductor, wiper *b* of the group selector GW , contact **29p**, winding of the metering relay Z_r , contact **27c**, earth. The double contact **34zr** closes and short circuits the resistance W_{14} in the locking conductor producing a current in this conductor which steps on the meter of the calling subscriber. The release of relay P in the group selector brought about by its winding III being short circuited at contact **37zr** leads to disconnection in the known manner.

When a local connection is set up by the subscriber T_{n2} the stepping on of the subscriber's meter Z_2 takes place when the connection is terminated. The switching operation for completing the connection and for controlling the meter corresponds completely to that occurring in the case of a local connection for the subscriber T_{n1} . The locking conductor in the preselector of the subscriber's station T_{n2} is differentiated from that of the subscriber T_{n1} only in that the alternating current phase relay E is connected parallel to the cut-off relay in the case of subscriber T_{n2} . Moreover between the subscriber's meter and the contact of the cut-off relay which locks the line after it has been tested, a low resistance circuit SpK is connected. These different switch means have, however, no control over the switching operations which occur at a local connection. The current increase on the locking conductor affects this subscriber in the same manner so that the subscriber's meter Z_2 is stepped on by one unit over: wiper *c* of the preselector VW_2 , meter Z_2 , locking circuit SpK , contact **25t2**, wiper *d* of the preselector VW_2 , battery, earth.

A high valued connection as set up by the subscriber T_{n1} will now be described. The setting of the group selector takes place in principle in the same manner but the wipers are elevated to a contact bank to which a repeater UE is connected for time zone metering. When such a free repeater is found the following test circuit is completed: earth, contacts **41c**, **40a**, windings I and II of relay P, wiper *c* of group selector GW , winding of the relay C_1 in the repeater and battery potential in a subsequent device. The relay P in the group selector operates in this circuit bringing about the switching operations already mentioned, and the relay C_1 in the repeater UE is also energised. Further impulse trains transmitted from the subscriber are transferred to the repeater UE over the following circuit by intermittent closing of contact **39a**: earth, contacts **41c**, **39a**, **28p** wiper *a* of the group selector, contacts **46g**, **47y**, winding of the relay A_1 , battery, earth. In manner

not shown here, the impulses are transmitted to the subsequent connecting arrangement by means of a contact of the relay A1.

When the connection for the calling subscriber is completed and the called subscriber replies, the relay G in the repeater is operated by means of battery potential which is applied to the lower talking conductor; battery in a further connecting device, lower talking conductor, contacts 54g, 55y, winding I of relay G, earth. The relay G locks up in the following circuit: earth, contacts 66c1, 69g (closed before contact 54g opened) 70y, winding II of relay G, battery, earth. Further the relay G closes the following circuit: earth, contacts 56c1, 57y, 59g, 60w, winding I of relay X, battery, earth. The relay X at contact 68x secures the circuit for the winding II of relay G independently of contact 70y. Further it opens the double contact 63x/64x so that the following circuit is completed: earth, contacts 56c1, 61g, 62w, winding II of relay X, winding of relay Y, resistance W1, battery, earth. In this circuit the relay Y operates and the relay X is further held energized. Contact 57y opens and breaks the circuit for the winding I of the relay X while the circuit for winding II of relay X and relay Y is completed independently of contact 61g by the closing of contact 58y.

When the calling subscriber hangs up and so terminates the connection, the relay A in the group selector GW restores. At contact 31a the winding I of the relay C is short-circuited so that it restores after a short interval. Contact 21c closes and connects earth potential to the metering relay Zr which is connected to the lower talking conductor. Relay P is not de-energised when its winding II is short-circuited by means of contact 43c since in the meanwhile the following circuit has been completed for winding III of relay P: earth, battery, winding III of relay P, contact 38c, upper talking conductor, contact 28p, wiper a of the group selector GW, contact 45g in the repeater UE, winding of relay W, contact 44s, earth. Since relay P continues to be energised the talking conductors remain switched through and the connecting path is held at the contacts 30p and 42p.

When as in the present instance, a high valued connection is set up by the calling subscriber, the bank contact DK in the group selector is closed. Alternating current is connected therefore, over a condenser, bank contact DK and contacts 36c and 35zr, in addition to direct current. The alternating current is so selected that it does not disturb the blocking operations. When a subscriber, whose fee is indicated by a meter at the exchange, makes a call the alternating current connected does not perform any operations and therefore, in this case, remains without effect.

In the repeater UE in the same circuit as that in which the relay P in the group selector is energised over its winding III the relay W is also energised. The relay W completes a holding circuit for winding II of relay G at contact 67w independently of contacts 68x, 69g and 70y. Further contact 62w opens and breaks a circuit for the winding II of relay X and for relay Y so that these relays are de-energised. A further connection of winding I of relay X is rendered impossible by the opening of contact 60w. A further holding circuit is completed for relay G over contact 70y.

In known manner, relay W in the repeater transmits the signal for the termination of the

conversation and the arrangements provided in the repeater for determining and transmitting the metering impulses are connected, this not being represented here in detail. Contact 53zr, which is closed a number of times corresponding to the number of impulses to be transmitted, is shown. The metering impulses produced by this contact are transmitted over the following path to the metering relay Zr in the group selector: earth, battery, contacts 53zr, 51y, 50w, lower talking conductor, wiper b of the group selector GW, contact 29p, winding of the metering relay Zr, contact 27c, earth. The metering relay Zr operates the double contact 34zr a number of times corresponding to the transmitted metering impulse whereby the resistance W1 is short-circuited at each interruption and a current increase is produced on the locking conductor which steps-on the meter Z1 of the subscriber Tn1. When the metering impulse is completed then the metering discriminating relay S (not shown) in the repeater UE is operated in known manner and contact 44s is now opened. The seizing circuit in which the relay W in the repeater UE and relay P, winding III, in the group selector are energised, is thereby interrupted and both relays restore. Contact 42p in the group selector opens and the holding earth is disconnected from the guard conductor extending to the subsequent junction arrangements and thus the signal for the release is transmitted. Contact 30p also opens holding earth is disconnected and the signal for release is given to the subscriber. In the preselector, therefore, relay T1 restores and in known manner the preselector VW1 is returned to its normal position. The release of relay P also effects the release of the group selectors in a manner which is not shown.

In the repeater after the opening of contact 42p the relay C1 is restored so that contacts 56c1 and 66c1 are opened. At the latter contact the circuit for relay G is finally interrupted.

In the connection described above the relay G in the repeater UE remains energised without interruption until the release of the connecting path takes place after the completion of the connection and transmission of metering impulses. The printing arrangement in the repeater is indicated by the reference RE. This printer mechanism per se does not form a part of the present invention, but, for example, it may be of the type disclosed in the R. Tilden et al, Patent 1,793,761, issued February 24, 1931, or in the C. I. Lattig Patent 2,010,868, issued August 13, 1935. Connection of the printing mechanism to the upper talking conductor is possible only over back contact 46g and operated contact 48y. Since, however, the release of relay G takes place only during the release of the connecting path i. e. when relay Y is already restored, the printing arrangement is not operated for this connection.

The operations occurring when subscriber Tn2 sets up a high valued connection during which the printing mechanism is brought into use will now be described. The printing mechanism which is centrally situated in the exchange must record the number of the calling subscriber as essential information. In the present embodiment the arrangement is such that by means of an impulse sender associated individually with the calling station impulse trains corresponding to the call number are transmitted over the talking conductors to the printing apparatus RE

which may be associated with the repeater UE. It is assumed that an arrangement is provided in the exchange which contains marking signals for numbers of subscribers. It may consist of a common, continuously operated shaft on which a series of impulse wheels are arranged each of which can transmit the impulse trains corresponding to the call number of a particular subscriber.

The operations are described more nearly in the following. When the subscriber T_{n2} lifts the receiver for the purpose of initiating a high valued connection the relay $R2$ in the preselector $VW2$ operates in the circuit: earth, winding of relay $R2$, contact $14t2$, lower talking conductor, contact $16e$, junction line $AL2$, subscriber's station T_{n2} , junction line, contacts $8e$, $13t2$, resistance $Wi2$, battery, earth. Contact $24r2$ closes and energises the rotary magnet $D2$ of the preselector $VW2$: earth, battery, wiper d of the preselector $VW2$ in the normal position, contacts $24r2$, $26t2$, magnet $D2$, relay interrupter $RU2$, earth. The wipers of the preselector are stepped-on under the control of the relay interrupter until they connect with a free group selector. When this occurs the following test circuit is completed: earth, battery, wiper d of the preselector in the operated position, contact $24r2$, windings II and I of relay $T2$, wiper c of the preselector, resistance $Wi3$, contact $31a$, resistance $Wi5$, off normal contact $33k$, earth. The relay $T2$ which operates in this circuit opens contact $26t2$ stopping the rotary switch and by disconnecting the high resistance winding II of relay $T2$ at contact $25t2$, guards the free group selector which has been selected against seizing by another line. Between contact $25t2$ and the winding I of relay $T2$, a low resistance circuit is connected to the talking conductor the low resistance circuit being of such a nature that it does not disturb the blocking operations. Contacts $13t2$ and $14t2$ open and break the circuit for the relay $R2$ in the preselector. Contacts $12t2$ and $15t2$ close and the talking conductors are switched through. Thus the following circuit by which the subscriber's station is provided with feeding current is completed: earth, battery, winding of relay A , wiper a of the preselector $VW2$, contacts $12t2$, $8e$, subscriber's loop, contacts $16e$, $15t2$, wiper b of the preselector, choke Dr , earth. Relay A in the group selector is energised and relay C is energised since contact $31a$ opens and removes the short circuit from the winding I of relay C .

The subscriber now transmits the first impulse train by which the group selector is stepped on to a contact bank over which a repeater UE is reached in known manner not shown. When the wipers of the group selector select a free repeater the following circuit is completed: earth, contacts $41c$, $40a$, windings I and II of relay P , wiper c of the group selector, winding of the relay $C1$ in the repeater, battery potential in a subsequent connecting device. In the group selector the relay P operates and, in the repeater, the relay $C1$. Contacts $28p$ and $29p$ close causing the talking conductors to be switched through and, contact $42p$ closes and locks the selected repeater against seizing by a further switch. The locking conductor is connected with holding earth over contact $30p$ and thus the connection is held independently of contact $32c$. Since the subscriber T_{n2} is making a high valued call the first impulse train closes the bank contact DK .

The further impulse trains transmitted by the subscriber are forwarded, as already described, by means of contact $39a$ to the impulse receiving relay $A1$ of the repeater UE and then in a manner not described to subsequent junction devices.

The connecting path is established, the called subscriber replies, battery potential is connected to the lower talking conductor from a subsequent connecting device over contacts $54g$ and $55y$ and relay G is energised over its winding I. Contact $69g$ closes locking relay C over its winding II. Further, as already described winding I of relay X is energised over contact $59g$ and opens the double contacts $63x$ and $64x$ causing the relay Y to energise over contact $61g$ while relay X is maintained energised over winding II. This circuit is locked by contact $58y$. The circuit for the winding II of relay G is maintained over contact $68x$.

When, on the completion of the connection, the subscriber T_{n2} hangs up, the relay A in the group selector restores, and by closing contact $31a$ restores relay C . The relay P is maintained energised over winding III and contact $38c$ in the previously mentioned seizing circuit and relay W in the repeater UE is also energised. Contact $36c$ closes and alternating current is connected to the talking conductor over the bank contact DK in its operating position and contact $35r$ whereby the alternating current phase relay E connected in parallel to relay $T2$ in the preselector and connected by means of contact $16t$ to the locking conductor is energised over both windings I and II. Contacts $8e$ and $16e$ open and disconnect the subscriber from the connecting path by opening the speech leads. The following circuit is completed: earth, battery, winding III of relay E , contacts $23f$, $22So$, $21f$ or $20U$, $17e$, $15t2$, wiper b of the preselector $VW2$, lamp GL , winding II of the relay C , earth. The lamp is lighted by the increased potential so that relay C is again energised over its winding II. Relay C opens its contact $38c$ and thus breaks the seizing circuit in which the relay P in the group selector and the relay W of the repeater were energised. The relay W in the repeater thus restores while relay P remains energised since its winding II is again connected in circuit by the opening of contact $43c$. Relay W in the repeater is therefore only energised for a short interval during which the following operations occur in the repeater: The circuit: earth, contacts $56c1$, $58y$ or $61g$, $62w$, winding II of relay X , winding of relay Y , resistance $Wi1$, battery, earth, is opened at contact $62w$ for a short interval. The relay X is finally restored during this interval while the relay Y , having a delayed armature release, remains energised in the following circuit after relay W releases: earth, contacts $56c1$, $58y$, $62w$, $63x$, winding of relay Y , resistance $Wi1$, battery, earth. The relay G also restores, since its holding winding II is disconnected at contacts $67w$, $68x$ and $70y$. In the repeater therefore the seizing relay $C1$ and relay Y only are energised. The printing apparatus is connected to the upper talking conductor over the restored contact $46g$ and the operated contact $48y$. Earth potential is connected to the printing apparatus over contacts $41c$, $39a$, $28p$, wiper a of the group selector, contacts $46g$, $48y$. If a printing apparatus is associated individually with the repeater UE, the printing apparatus is prepared for use by the earth connection so that the impulses which

follow, indicating the call number, are received and registered. The arrangement can, however, be such that a number of printing apparatus are provided in common in a number of repeaters. The connection of earth potential in this instance serves as an impulse for finding and connecting a free printing apparatus to the repeater concerned.

The impulse sending arrangement associated with the preselector VW2 is so connected that various contact operations take place mechanically. This is illustrated in Fig. 2. The contact movements corresponding to the call number of the subscriber Tn2 are indicated by J and are generated by an impulse wheel. In the present example it is assumed that the subscriber has the call number 4216, the impulse wheel therefore is in a position to transmit the impulse trains corresponding to the individual digits of this number by intermittent operation of contact 11j. S indicates a contact arrangement which opens contact 22so for a short period previous to the transmission of the impulse trains by the impulse wheel. After the transmission of the impulse trains contact arrangement U operates first contact 20u alone and then contacts 20u and 19u together.

When the impulse sending arrangement is in such a position that contact 22so is opened, the short circuit of the winding of the relay F is removed and this relay is energised in the above-mentioned circuit together with the winding III of relay E and winding II of the relay C in the group selector. Contact 23f opens and ensures that relay F is not short circuited on the release of contact 22so. At contact 10f the contact 11j operated by the impulse wheel is connected over contact 9e to the upper talking conductor and the following circuit is closed: earth, contacts 11j, 10f, 9e, 12t2, wiper a of the preselector VW2, winding of the relay A in the group selector, battery, earth. The relay A operates in this circuit and opening contact 39a prevents the connection of earth potential to the upper conductor and hence to the printing arrangement RE which is now prepared to receive impulses. Contact 11j operates and transmits impulses which interrupt the circuit for relay A. The relay A now transmits the impulses sent out from the impulse wheel to the printing apparatus in the repeater earth, contacts 41c, 39a, 28p wiper a of the group selector GW, contacts 46g, 48y, printing apparatus RE. In the printing apparatus the different type wheels are positioned on the individual digits of the call number of the calling subscriber by means of the individual impulse. In the interval between individual impulse trains it is possible to change over from one printing wheel to another in the printing apparatus.

Simultaneously with the impulse trains corresponding to the call number, metering impulses may be transmitted from the time zone repeater over the following path: earth, battery, metering contact 53z, which is operated a number of times corresponding to the number of units to be recorded, contact 52y printing apparatus RE.

When the call number has been transmitted to the printing mechanism the operated contact 20u is closed without interrupting the rest contact (provision being made for make before break). The following circuit is completed: earth, contacts 18f, 19u, 20u winding of the relay F, winding III of the relay E, battery, earth.

In this circuit the relays E and F are energised for the time being. Rest contact 20u opens and disconnects the potential from the lower talking conductor so that relay C in the group selector restores.

5 Contact 11j is operated again simultaneously with contact 20u (see Fig. 2). Since earth potential is disconnected from the upper talking conductor by the release of contact 11j relay A in the group selector is de-energised.

10 Relay C in the group selector now releases and leads to the release of the connection. Winding II of relay P is short circuited at contact 43c causing its contacts to restore since, no earth potential being available from the repeater, its winding III can no longer remain energised. Contacts 30p and 42p open and remove holding earth from the blocking conductors extending to the call subscriber and to the repeater. In 15 the repeater the relay C1 restores and breaks the circuit for relay Y by opening contact 56c1.

20 In the preselector the holding circuit for relays E and F is broken by the operation of contact 19u sometime after the operation of contact 20u and the relays restore.

25 The remaining operations required for the release are not explained further since they are known and are not essential for the invention.

30 The differentiation between the high value connections set up between the subscriber Tn1 and the ones set up by the subscriber Tn2 resides in that, relay C is restored permanently after the terminating signal transmission from the subscriber Tn1 while, on the transmission 35 of the terminating signal from subscriber Tn2, relay C restores only for a short period and then operates again. During the short release period of relay C a circuit is opened in which are connected a normal and a slow-to-release relay. 40 The normal relay only is restored while the slow-to-release relay remains energised and is used for connecting the printing apparatus.

45 It should be mentioned that other information may be transmitted and registered by the printing apparatus. The recording of the date and the time is conveniently performed within the printing device. Thus, since the printing apparatus is associated with the repeater for time zone metering i. e. is situated at the station where the stepping devices for the meter are situated, the required direction may easily be obtained from the switching device (zone switch) which is provided for the marking operation and a corresponding marking signal may be transmitted to the printing arrangement 50 after the connection is set up.

55 If it is required to record the calling number storage elements which take up the impulses transmitted from the subscriber and transmit these to the printing apparatus may be associated with the repeater after the printing apparatus is connected.

60 I claim:

1. In a telephone system, two groups of subscribers' lines, the subscribers' lines in one of said groups each provided with a call recording meter to register calls, the subscribers' lines in the other of said groups each provided with a switching means for transmitting impulses corresponding to its associated subscriber's telephone number, a repeater accessible to said lines, means in said repeater operated responsive to the completion of a call thereover by a subscriber in said one group of lines for controlling the said subscriber's associated call recording

meter, a printing mechanism, and means in said repeater operated responsive only to the completion of a call thereover by a subscriber in said other group of lines for connecting said printing mechanism thereto to record the number transmitted by said last-mentioned subscriber's switching means.

2. In a telephone system as claimed in claim 1 wherein there are connecting devices associated with said repeater for connecting said printing mechanism to said repeater, and means in said switching means for transmitting a signal to operate said connecting devices.

3. In a telephone system as claimed in claim 1 wherein the means for associating said printing mechanism with said repeater comprises a plurality of relays associated with said repeater, and means in said switching means for transmitting a signal to operate said relays.

4. In a telephone system as claimed in claim 1 wherein the subscribers' lines have access to said repeater by means of a line switch individual to each of said subscribers and wherein the said switching means is controlled over a test conductor including a wiper of said line-switch by an alteration in current strength thereover to thereby transmit the calling subscriber's telephone number.

5. In a telephone system as claimed in claim 1 wherein there is a switch for connecting said lines with said repeater, and means in said switch operated by said switching means for controlling the operation of the printer mechanism connecting means in said repeater.

6. In a telephone system, an automatic switch, a trunk line, a subscriber's line, means controlled by said subscriber for extending a connection via said switch to said trunk line, a telephone number transmitting device individual to said subscriber's line, means responsive to the termination of said connection for disconnecting said subscriber from said switch and connecting said device thereto, a printer mechanism, means in said trunk line operated responsive to the connection of said device to said switch for operatively associating said mechanism with said trunk, and means in said device operated responsive to connecting with said switch for transmitting said subscriber's telephone number to said mechanism to record the same.

7. In a telephone system, a repeater, a first class and a second class of subscribers' lines, means for extending a connection from any line to said repeater, means associated with said repeater for transmitting meter operating pulses to a subscriber's meter, a printer mechanism, means in said repeater for associating said printer mechanism with said repeater to record subscribers' telephone numbers, said repeater operated responsive to the termination of a connection established thereover for connecting said meter pulse transmitting means thereto only when a subscriber in said first class of lines has extended the connection and for associating said printer with said connection when a subscriber in said second class of lines has extended the connection, means individual to each of the lines in said first class of lines for recording the number of said meter pulses, and means individual to each of the lines in said second class of lines for transmitting the number of the subscriber that has extended the call to the printer mechanism.

8. In a telephone system, a main exchange, toll lines, subscribers' lines terminating in said

exchange, switches controllable by calling subscribers to extend connections over said toll lines, said subscribers' lines divided into first class and second class lines, the lines in a first of said classes provided with individual message registers, means associated with said toll lines for discriminating between the classes of lines extending connections over said toll lines, said discriminating means operated in one manner only in the event that a subscriber in the first of said classes of lines has extended the connection to transmit impulses to control the operation of that subscriber's message register, a printer mechanism, said discriminating means operated in another manner to associate said printer with said toll line only in the event that a subscriber in the second of said classes of lines has extended the connection, and means individual to each line in the second of said classes of lines for transmitting the associated subscriber's telephone number to said printer mechanism.

9. In a telephone system, automatic switches for extending toll and local calls, a subscriber's line having access to said switches, an impulse transmitting device individual to said line and normally disconnected therefrom, a call register individual to said line, means in said switch train operated responsive to the termination of a local connection extended from said line for operating said call register, a printing mechanism, means in said switch train operated responsive to the termination of a toll connection extended from said line for associating said printing mechanism with said switch train, and means also operated responsive to the termination of said toll connection for disconnecting said line from said switch train and for connecting said impulse transmitter thereto, said transmitter transmitting impulses to operate said printer and thereby record the subscriber's telephone number.

10. In a telephone system, a first and second subscribers' line, a toll line, automatic switches controllable from said lines to extend calls over said toll line, a register for said first line, an impulse transmitter for transmitting said second subscriber's telephone number, means in said toll line operated only responsive to the termination of a toll call extended from said first subscriber's line for controlling said register to register the call, a registering mechanism, means in said toll line operated only responsive to the termination of a toll call extended from said second subscriber's line for associating said registering mechanism with said toll line, and means thereafter controlled by said impulse transmitter for operating said registering mechanism to register said second subscriber's number.

11. In a telephone system, a train of automatic switches including a repeater, two classes of lines having access to said train of switches, a call recording device associated with each line in one of said classes of lines, a line number identifying device associated with each line in the other of said classes of lines, means in said repeater operated only responsive to a connection established thereover from any line in said one class of lines for transmitting pulses to control the call recording device of the calling line, and means in said repeater operated only responsive to a connection established thereover from any line in said other class of lines for connecting a register to said repeater to record the calling line number transmitted by the associated identifying device.

12. In a telephone system, subscriber's lines

divided into a first and second group, means individual to each line in said first group for registering completed calls, means individual to each line in said second group for transmitting the telephone number of its associated calling subscriber, a train of automatic switches, means in one of the switches in said train operated responsive to the completion of a call thereover by a subscriber in said first group for operating the said subscriber's registering means accordingly, a printing mechanism, means in one of the switches in said train operated responsive to the completion of a call thereover by a subscriber in said second group for associating said printer with said switch train, and means in one of said switches operated by the transmitting means individual to the calling subscriber for controlling said printer to register the number of the calling subscriber.

13. In a telephone system, subscribers' lines of one class, subscribers' lines of a different class, service meters one for each of said lines in said one class, a printing mechanism, means controlled on a time zone metering basis for operating said meters and said printing device, said last-mentioned means operating the meter individual to the line of a calling subscriber of said one class a variable number of times responsive to the completion of a connection by the said calling subscriber and operating said printing mechanism a variable number of times responsive to the completion of a connection by a calling subscriber of said different class of lines to thereby assess a charge against the calling subscriber in accordance with the duration and destination of the call, and means individual to each of the subscribers' lines of said different class operated responsive to the completion of a connection for transmitting the telephone number of its associated calling subscriber to said printing mechanism to identify the subscriber to be charged.

14. In a telephone system, two groups of subscribers' lines, the subscribers' lines in one of said groups each provided with a call recording meter, the subscribers' lines in the other of said groups each provided with a switching means for transmitting the telephone number of its associated line, a repeater accessible to said lines, means operated responsive to the completion of a call including said repeater extended by a subscriber in the said one of said groups of lines for controlling the subscriber's individual call recording meter a variable number of times according to the destination of said call, a printing mechanism, and means operated responsive to the completion of a call including said repeater extended by a subscriber in the said other of said groups of lines for initiating the operation of the said calling subscriber's telephone number switching means and for connecting said printing mechanism to said repeater to thereby record the telephone number transmitted by the said switching means.

15. In a telephone system, two groups of subscribers' lines, each of said subscribers' lines in one of said groups provided with a call recording meter for registering calls, a switch accessible to said lines, a printing mechanism individual to said switch, and means operated responsive to the completion of a call including said switch for operating the calling subscriber's associated meter a variable number of times when the calling subscriber is one of the subscribers in said one group and for operating said printing mechanism a variable number of

times when the calling subscriber is any one of the subscribers in the other of said groups of lines to thereby make a charge for the call in accordance with the destination of the completed call.

16. In a telephone system, two groups of subscribers' lines, each of the subscribers' lines in one of said groups provided with a call recording meter for registering calls, each of the subscribers' lines in the other of said groups provided with a transmitter for transmitting the telephone number of its associated subscriber's line, a switch accessible to said lines, a printing mechanism, means operated responsive to the completion of a call including said switch for operating the calling subscriber's associated meter a variable number of times when the calling subscriber is one of the subscribers in said one group and for operating said printing mechanism a variable number of times when the calling subscriber is one of the subscribers in said other group of lines to thereby make a charge in accordance with the destination of the completed call, means operated responsive to the completion of a call by a calling subscriber in said other group of lines for initiating the operation of said transmitter associated with the said calling subscriber's line, and means controlled by said transmitter for operating said printing mechanism to record the said calling subscriber's telephone number to thereby identify the record made by said printing mechanism of the destination of the said completed call.

17. In a telephone system wherein subscribers control automatic switches to extend connections, subscribers of a first class each provided with individual meters for registering calls, subscribers of a second class each provided with individual switching means for transmitting its associated subscriber's telephone number, means operated responsive to the completion of a connection by a subscriber of either class for transmitting a variable number of pulses in accordance with the destination of the completed call, a printing mechanism, said pulses controlling the calling subscriber's meter when a first class subscriber has completed the call and controlling said printing mechanism when a second class subscriber has completed the call, and means operated in the event that the call is completed by a second class subscriber for initiating the operation of the said second class calling subscriber's telephone number transmitting means whereby said printing mechanism is operated to record the telephone number of said second class calling subscriber.

18. In a telephone system, subscribers' lines of one class, subscribers' lines of a different class, service meters one for each of said lines in said one class, a printing mechanism common to the lines of said different class, and means controlled on a time zone metering basis for operating said meters or said printing device, said last-mentioned means operating the service meter individual to the line of a calling subscriber of said one class a variable number of times responsive to the completion of a connection by the said calling subscriber and operating said printing mechanism a variable number of times responsive to the completion of a connection by a calling subscriber of said different class of lines to thereby assess a charge against the calling subscriber in accordance with the duration and destination of the call.

19. In a telephone system, two groups of sub-

scribers' lines, each of the subscribers' lines in one of said groups provided with a call recording meter for registering calls, a switch accessible to said lines, a printing mechanism individual to said switch, and means for controlling the call recording meter of a calling subscriber a variable number of times in accordance with the destination of a call completed via said switch by any subscriber in the said one group of lines and for controlling said printing mechanism in accordance with the destination of a call completed via said switch by any subscriber in the said other group of lines.

20. In a telephone system, two groups of subscriber lines, each of the subscriber lines in one of said groups being provided with a meter for registering calls, printing mechanism operative to produce a record of the pertinent items pertaining to a call, a link, means for setting up a call from a calling subscriber line in either one of said groups via said link, and means included in said link and governed in accordance with the one of said groups including said calling subscriber line for selectively controlling the meter individually associated with said calling subscriber line or said printing mechanism, whereby the meter individually associated with said calling subscriber line is operated a variable num-

ber of times in accordance with the destination of the call in the event said calling subscriber line is included in said one group of lines or said printing mechanism is selectively operated in accordance with the destination of the call in the event said calling subscriber line is included in the other of said groups of lines.

21. In a telephone system, a first and a second group of subscriber lines, each line in said first group provided with a call recording meter, a repeater accessible to all of the lines, a printing mechanism operatively associated with said repeater, means for completing a telephone connection including said repeater from a calling subscriber line in either of said groups to a called subscriber line, and means in said repeater for selectively controlling the call recording meter of the calling subscriber line in accordance with the destination of a call in the event that the call is completed from a subscriber in said first group and for selectively controlling said printing mechanism in accordance with the destination of a call in the event that the call is completed from a calling subscriber line in said second group, whereby a charge is made according to the destination of a call.

FRITZ WOLF.
